KNITTING MACHINE FOR WRAP STRIPING

Frederick Edward Deans and Carlyle Herbert Wainwright, Leicester, England, assignors to The Bentley Engineering Company Limited, Leicester, England

Application September 4, 1946, Serial No. 694,731
In Great Britain September 12, 1945

4 Claims. (Cl. 66—135)

1

This invention is concerned with the production, in machine-knitted fabric and articles, of patterns by what is known as "wrap striping" wherein threads, additional to the ground thread of which the fabric is in the main knitted, are wrapped round selected needles and, being incorporated with the ground thread in selected needle loops, impart a patterned appearance to the fabric. An object of the present invention is to provide for the introduction of a plurality of 10 colours in one and the same course of a panel of the fabric.

The invention provides a method of wrap striping or patterning in which a plurality of wrap threads is fed in a course, which consists in employing a separate wrap finger for each thread, traversing said wrap fingers one after another past one and the same group of needles, and for each traverse positioning at a thread receiving height only the needle or needles required to receive thread at that traverse. Preferably the wrapping is effected before the needles clear the loops of the previous course, selected needles being raised, to a height less than the clearing height, for each wrapping traverse to receive the wrap thread. In the case of the needle or needles raised to receive the first wrap thread, said needle or needles is or are subsequently lowered to avoid the second wrap thread; the expression "raised" as employed herein is to be interpreted as including a condition in which the said needle is or needles are retained at a level above the remainder.

It is further preferred that the wrapping traverse in relation to the needles shall be in the opposite direction to the relative traverse between the needles and their knitting cams or other operating means. Thus, in the case of a rotating needle cylinder machine, the relative traverse is effected by causing the wrap fingers to lag behind the needles.

The foregoing and other features of the invention set out in the appended claims are incorporated in the mechanism, primarily suitable for a circular knitting machine of the superimposed needle cylinder type wherein the cylinders rotate (such as that sold under the registered trade-mark "Komet"), which is hereinafter described with reference to the accompanying drawings wherein

Figure 1 is a front elevation of the relevant parts of the machine, showing wrap fingers, wrap finger carrier, and associated parts, but with the upper needle cylinder and cam box omitted;

Figures 2 and 2A are a sectional elevation,

2

taken on a substantially radial plane, through the upper needle cylinder and cam box;

Figure 3 is a sectional plan taken on the line A—A in Fig. 1;

Figure 4 is a perspective view of a stop plate;

Figure 5 is a perspective view illustrating a detail in elevation.

Figure 6 shows the cams of the bottom cam box.

It is to be remarked that since knitting machines of the type referred to are themselves well known, the appended drawings show only so much of the knitting machine as will permit it to be identified and as is necessary to make clear, to one well acquainted with the construction of this type of machine, the application of the present mechanism thereto. Thus, the top and bottom cylinders are shown at 1 and 2, the top cam box at 3, the double-ended needles at 4, and the top sliders at 5. The method on which 15 said mechanism operates consists in advancing, at a wrapping zone, a wrap thread guide or finger 6 (which rotates with the needle cylinders and is provided at each location in the circle whereat it is desired to supply a wrap thread) at the inside of the needle circle towards the knitting point, so that in effect it overtakes a group of the needles, projecting it outwards across the needle circle, holding it stationary so that it lags behind said group of needles and the latter overtakes it with the result that such needles thereof as may have been selectively raised (or maintained in a relatively raised position) receive this thread, and then moving it inwards across the needle circle.

35 In the present construction, the wrap thread guider or finger 6 is a long blade-like member mounted inside the upper or rib-needle cylinder 1 and having a thread guiding portion or toe 7 at or near the lower end. It is carried, at the required location in the needle circle, in a groove in a cylindrical carrier 8 (inside and rotating with needle cylinder 1) and is shaped so that it can rock at the wrapping zone in the groove, whereby it receives a radial movement which takes the 40 thread guiding end 7 across the needle circle. The fulcrum point 9 is intermediate the ends and the upper end is arranged (e. g. with butt 10) so that it can be acted upon by cams or the equivalent 11 at said zone to move the thread 45 guiding end 7 across the needle circle. The cams 11 may act in both directions or in one direction only and the finger returned by a spring 12, being stopped from excessive movement by a stop 13 on the bobbin carrier 14 on which a supply bobbin 15 for each wrap finger may be mounted.

The wrap finger 6 is housed in the groove in the carrier 8 for preferably only the upper portion of its length, the carrier 8 extending from level 16 near the upper end of the finger to level 17 a little below the fulcrum point 9. The lower part is then free to be deflected laterally to provide the movement, circumferentially of the needle circle, which causes it to overtake the needles of the group with which it co-operates and to be positioned at the leading end of the group (the leading end being that end which arrives first at the knitting point); this overtaking movement is hereinbefore referred to as the advance of the finger. Thus, the direction of rotation of the needle cylinders 1 and 2 and of the carrier 8 being anti-clockwise in Figure 3, the finger moves to the right hand end of the group of needles shown in Figures 1 and 3. The flexing of this finger 6 to give this movement is preferably restricted to a comparatively short length of the finger say about one inch, immediately below the carrier 8, in order to give a more definite and uniform movement to the thread guiding end 7, with the vertical component of the movement a minimum. This restriction of the flexing may be achieved by making the finger in a stiffer section in the part which is not required to flex either by the formation of the finger itself or by attaching a stiffening piece 18. In the latter case, the stiffening piece may incorporate a projection 19 to be engaged to deflect the finger. One method by which the deflection of the finger 6 may be carried out consists of mounting a deflecting piece 20 in a groove in the carrier 8, spaced a short distance from the groove housing the finger 6 and parallel to that groove. The lower end of the deflecting piece 20 engages the projection 19 on the finger and is operated to slide in its groove, for instance by a projecting butt 21 engaging cams 22, 22a, at or near its upper end, to bring about the deflection. The engagement between the deflecting piece 20 and the projection 19 on the finger 6 may be a hinged connection so that the finger is deflected in both directions and controlled throughout its movement by the deflecting piece or the engagement may be merely contact so that the finger is deflected in one direction only by the deflecting piece and returned by other means. In the illustrated construction the latter method is adopted, and the finger 6 is made of springy material and set so that when free it tends to lie a little beyond the rear extremity of its intended starting or rest position at the trailing (or left hand) end of the group of needles (Fig. 3) with which it co-operates (the trailing end of the group being that end which arrives last at the knitting point). A rear stop 23 holds the finger 6 up to its starting position and when the finger is deflected by the deflecting piece 20 and released it will return by its own springiness to the stop 23. The extent of the deflection is determined by the movement given to the deflecting piece 20 and is preferably a little more than enough to advance the finger 6 to the position for projection across the needle circle. The exact position for projection is determined by a spring front stop 24 which yields downwards as the finger 6 is moved by the deflecting piece 20 and springs up into place as the finger approaches the end of its movement and thus holds the finger in the exact position at the leading end of the group needles for projection as the deflecting piece is withdrawn. The spring stop 24 may consist in merely a spring blade, the rear

end of which is anchored at 25 in a position clear of the finger 6 and the front end of which lies in the path of the finger and is shaped so that it is brushed aside (e. g. pressed down) as the finger advances towards its position for projection. The outer edge 24' of front stop 24 is so placed that as the finger 6 is projected outwards across the needle circle the heel 26 of the finger remains in contact with the stop 24 until the yarn guiding portion or toe 7 of the finger is safely outside of the needle circle. At this stage, the back edge 26' of the heel 26 has passed outwards beyond the edge 24' of stop 24 and the cleft or instep 27 between heel and toe spans the needle line (see Fig. 2); therefore the finger 6 tends to spring immediately to the fixed stop 23 at the other end of its movement. This movement however, is delayed by the presence of a stationary abutment 28 placed outside the needle circle in such a position that the toe 7 of the finger 6 rests on it as soon as the finger becomes free from the spring stop 24. The object of the abutment 28 is to prevent the sudden snap of the finger 6 to its rear stop 23 with the consequent tendency to break the yarn. The finger 6 is therefore held stationary while the needles travel rotationally past it, with the result that the speed of the travel of the finger in relation to the group of needles towards the trailing end of said group is equal to that of the needles past the feeder 29 for the ground yarn. This is the wrapping traverse of the finger 6. It takes place before the needles of the group have cleared their old loops and during it selected needles are held in a raised position, which is less than the clearing height, so that the thread fed by the finger is laid on said needles above the old loops and above the spoons of the open latches. When the finger arrives at the trailing end of the group it is retracted within the needle circle by spring 12 and continues to rotate with the needle cylinder 1. The needles that have just been wrapped are subsequently lowered to joint the remainder. It will therefore be seen that the finger, or rather its thread-feeding part, moves unidirectionally in a closed circuit at each course wherein wrapping is to take place, the successive circuits being made in one and the same direction.

Preferably the abutment 28 is mounted to yield in the direction of rotation (in the case of a rotating cylinder machine) so that if the finger 6 is projected outwards a little before its correct time the abutment will be brushed aside and no part of the machine will be damaged. Therefore the abutment 28 is carried by a lever 30 which is normally stationary and is freely mounted on pin 31 and is urged by spring 32 against a positioning stop 33.

In order to make patterns in the fabric having two colours in the same panel and in the same course of knitting it has been proposed to lay the two yarns simultaneously on needles at different levels, and to select the needles to be taken to three different levels, a low level in which neither yarn is taken, an intermediate level in which the low yarn is taken and the high yarn passed over the head of the needle, and a high level in which the high yarn is taken and the low yarn lies below the latch so that it is thrown over the head of the needle at the knitting point and does not appear on the face of the fabric.

The illustrated mechanism is constructed and arranged for the introduction of two colours, in the same panel or the group and in one and the same course of knitting, in two successive stages

instead of the single stage of the above mentioned prior proposal. Thus instead of feeding both wrap threads through two guide holes in one of the same finger, two separate fingers 6 and 6a are employed. The wrap fingers 6, 6a make their wrapping traverse one after another so that the wrapping is effected in two stages; both stages occur before the needles have cleared their old loops, and the selected needles are raised to a height less than clearing height. The needles that at the first stage receive the first wrap thread (from finger 6) above the spouts of their open latches and above the uncleared old loops, are lowered to rejoin the remaining needles of the group before the second stage; at the second stage other selected needles are raised to the wrapping height to receive the second wrap thread from finger 6a. Thereafter all needles of the group continue round to the knitting point whereat they all receive the ground yarn, and the loops of this ground yarn, together with the wrap thread loops on the selected needles, are drawn through the old loops and the latter are cast off. It will be appreciated that in these operations if one of the wrap threads floats (as in many instances it will), past a non-wrap needle between two wrapped needles, this float length is passed to the back of the non-wrap needle and does not appear at the outer face of the fabric.

It may here be pointed out that this sequence of operations necessarily involves a movement of the wrapping fingers 6, 6a, substantially circumferentially above the heads of the needles and the fact that wrapping takes place prior to clearing overcomes the difficulties that have been experienced in effecting such a movement in a machine of the superimposed needle cylinder type wherein there is little space between the two cylinders and between the rib and plain needles.

It is important to separate sufficiently the old main or ground loop and the wrap yarn or otherwise the wrap yarn will clear the latch at the same time as the main loop and will not then appear on the face of the fabric. This separation is not readily achieved without special means particularly when the first needle to be wrapped in one course is the last needle or very near the last needle wrapped in the previous course. The means employed for this purpose comprises a member 34 which lies immediately behind the needles and above the fabric and extends from the beginning of the wrapping zone to a point a little beyond that where the loops clear the latches. As an additional safety precaution, it is preferable to lower the needles slightly immediately after clearing so that it is impossible for the wrap yarns to get below the latches. The member for separating the yarns as just described may conveniently be formed from a piece of round wire attached at the beginning of the wrapping zone to a non-rotatable tube 35 located inside the top needle cylinder 1 so that the tube and wire remain stationary while the needles 4 revolve around them. The main loops are always below this member 34 and the wrap fingers 6, 6a pass above it to cross the needle circle and consequently lay the wrap yarns over the top of it. The wrap yarns slide along it until they slip off the free end just beyond the clearing point. The tube 35 is cut away, at the wrapping zone, at 36 so as to permit of the finger movements.

The two fingers 6, 6a are mounted either in the

same groove in the carrier 8 or one in each of two closely adjacent grooves, preferably the latter. It is convenient to identify them as being the "first" and "second" fingers, the first finger 6 being that which makes the first movement outside the needle circle, but being actually the finger which is the rear-most of the two. Only this first finger 6, which is the nearest to the deflecting piece 20 is provided with a projection 19 to be engaged by the latter but the second finger 6a (with a stiffener 18a) is simultaneously deflected by contact with the first one, so that both fingers make a simultaneous advance and have their position at a leading end of the group of needles determined by the spring stop 24 above-mentioned which engages the first finger 6. As soon as the first finger 6 is projected across the needle circle and thereby vacates its position at the spring stop 24, the second finger 6a springs against said stop so that it is ready in the same position for projection when its turn comes. The projected first finger 6, having been engaged by its fixed abutment 28, is held stationary so that the needles move on past it and the trailing end of the group eventually moves opposite it, at which stage the rear stop 23 catches up with it and causes it to travel ahead with the group of needles, away from its abutment 28; it is also swung inwards across the needle circle by its spring 12. This rear stop 23 is formed with either a stop or an incline 37 so that as soon as the first finger 6 is inside the needle circle a further slight inward movement of said finger causes its heel 26 to spring down the step or incline, thus leaving the stop vacant for the second finger 6a to be retracted (by its spring 12) at exactly the same point in the needle circle as was the first finger. The second finger 6a is of course projected outwards across the needle circle by cams 11 at a later stage than the first finger and engages a second yielding abutment 28a which is spaced circumferentially from the first abutment 28 (nearer to the knitting point), which second abutment holds it stationary until the trailing end of the group of needles arrives opposite it and the rear stop 23 engages it. It will therefore be appreciated that the fingers 6, 6a make their wrapping movement outside the needles one after the other.

Abutment 28a is mounted on lever 30a pivoted at 31a and urged by spring 32a against stop 33a. As the stops 23, 24 need to be placed with some precision so that the fingers are projected and retracted between two chosen needles, they are provided with means for adjustment so that they can be accurately set. For this purpose they are carried by or formed on a sector shaped plate 38 which is positioned on the upper surface of a dial 39 inside the needle circle and has near its outer edge a curved rim 40 slidably engaged in an annular groove 41 in the dial. The inner edge of this plate 38 is slidably received in a groove 42 formed between the upper surface of the dial and a member 43 attached to the dial boss 44, which member 43 also houses a wire or other ring 45 (preferably of circular cross section) which rests on the upper face of the buried end of the plate 38. A locking screw 46 is inserted radially in a suitably threaded hole in the member 43 and has a conical end which bears on the ring 45; thus by tightening the screw 46 the ring 45 is pressed down locally to grip the associated stop-carrying plate 38 and the position of the stops 23, 24 may readily be adjusted by slackening off the screw.

It has previously been mentioned that tube 35 remains stationary while the fingers 6, 6a rotate inside, and the cylinder 1 rotates outside it. To permit of this, the carrier 8 is driven by gear 53 (to which it is clamped by plate 52 and which has a bearing in stationary plate 54), the cylinder 1 is driven by gear 61 at a lower level, while the tube 35 is supported at an intermediate level by stationary casing 57. Tube 35 is locked by nut 56 to a ring 55 which is keyed to said casing, and in order that the height of the lower edge of the tube, and of the separating wire 34, may be adjusted the edge 58 of ring 55 is of cam-form and rests on a ring 59 having its co-operating upper edge also of cam-form so that by adjusting the cam ring 59 circumferentially within housing 57 by means of the protruding pin 60 the tube 35 may be raised and lowered.

Figure 6 is a development of the cams for the lower needle cylinder and also shows the needles 4, bottom sliders 5' and jacks 71. During circular knitting (e. g. during the knitting of the leg and foot of a seamless half hose or the like) the knitting butts 89 of the sliders 5' descend the knitting cam 81a and, bolt cams 67 and 68 being withdrawn, travel from right to left along the path indicated by the dotted line 66. Bolt cam 69 is operative and acts on the butts 79 of jacks 71 to raise all needles so that the knitting butts 89 engage clearing cam 74. When wrap striping is required, selected needles are raised to a non-clearing height, to take the wrap yarn supplied by finger 6, by means of cam 72 so that the knitting butts follow path 73; after taking the wrap thread they are lowered by cam 77. As the needles that have received this wrap thread descend cam 77 the wrap thread is supported by the separating member 34 at the points where said thread extends above said member. If a second wrap thread is to be supplied by finger 6a, a second selection is made at the second stage and the selected needles are raised to a non-clearing height by cam 75 to take the wrap thread fed by finger 6a the knitting butts following path 76. After taking this second thread the raised needles are not lowered but are cleared by cam 74, together with all unwrapped needles as well as those which took the first wrap thread: that is to say, by virtue of the operation if the separating member 34 only the old loops are cleared below the latches, but the newly applied wrap threads remain above the spools of the open latches. The butts of the cleared needles pass on over cam 81 and the needles take the main thread at feeder 29 and are lowered by cam 81a so that they all knit. It is here to be explained that since the needles that were supplied with wrapping thread arrive at the knitting cams with that thread still above the spools of their open latches, these needles pass loops of the wrap thread together with loops of the newly fed main yarn through the old loops that were cleared at cam 74. Any appropriate selecting mechanism may be employed to select needles to be raised by cams 72 and 75.

In oscillatory knitting, when knitting the heel, it is desirable to direct the idle instep needles into a low non-knitting track instead of into the usual high non-knitting track so that the wrap thread can be laid on the needles before their loops are cleared in the first rotary course following the heel. For this purpose, bolt cam 67 is inserted sufficiently to engage the long butts 89 associated with the instep needles and to direct them into the low track 78 but to miss the short butts

89 associated with the heel needles which short butts therefore follow track 79, bolt cam 68 being inserted to engage them. Bolt cam 69 is withdrawn to permit the idle instep needles to remain in the low non-knitting track throughout the heel. Cam 80 stands away from the cylinder sufficiently to miss the short knitting butts 89 but is closed enough to engage the long knitting butts. Thus, in a swing from left to right during the knitting of the heel, after the heel needles all knit by reason of their short butts 89 descending the full stitch cam 81 they are raised by cam 82 and are cleared by cam 83, but the long butts associated with the instep needles are directed by cam 80 into the low non-knitting track shown by a chain dotted line beneath cam 83. Picking is done in the usual manner. That is to say, the needles which knit the heel are gradually reduced in number by the end needle in each swing being raised to the high inactive loop-holding level 84, said needles being subsequently picked down again to the knitting track. A draw thread of the type described in British Patent Specification 400,623 may be knitted by cams 68 and 85 being inserted sufficiently to direct the butts 89 down track 86. 87 is the draw thread stitch cam and when a drawn thread is to be knitted it is lowered together with its guard cam 88 to a stitch-drawing position.

It will be appreciated that if it is desired to supply wrap thread or threads at more than one location in the needle wale, the appropriate fingers 6, 6a, are provided at each such location to operate as they arrive at the wrapping zone illustrated in the drawings.

The subject matter of U. S. Patent No. 2,463,751, of March 8, 1949, and U. S. patent application Serial No. 694,732, filed September 4, 1946, now abandoned, is disclosed in the present application, and the subject matter of the present application is disclosed in the above mentioned patent and patent application.

We claim:

1. In a knitting machine having a needle bed and relatively displaceable needle-operating means and needles in said bed, wrap striping mechanism for patterning by feeding a plurality of wrap threads in a course, comprising a separate wrap finger for each thread, means for traversing said fingers one after another past one and the same group of needles, means for positioning at a thread-receiving height in each traverse, only the needle or needles of said group required to receive the wrap thread fed at that traverse, and a separator, for separating the old loops from the wrap loops on the needles, located at the plain side of the needles below the path of movement of the fingers and extending along the needle line throughout the zone at which said fingers operate and having a free end at the end of said zone to permit the wrap loops to slip off it.

2. In a knitting machine of the superimposed needle cylinder type having rotatable needle cylinders equipped with latch needles and relatively-stationary needle-operating means; wrap striping or patterning mechanism for applying wraps threads at a wrapping zone to selected needles of at least one group thereof, comprising for each group two separate wrap fingers each for feeding a wrap thread and having thread guiding extremities, means mounting said fingers within the upper cylinder to rotate with the cylinders, means for operating said fingers to overtake the

needles of the associated group, to pass at the leading end of the group to the outside of the needle circle, to lag one after another behind said group in two successive wrapping traverses, and to retire within the circle at the trailing end of the group, and means for positioning a different selection of needles of said group at an elevated thread-receiving height in each traverse.

3. A machine according to claim 2, having a stationary tube located between the circle of needles and the fingers, which tube has a window at the wrapping zone to accommodate the fingers in their wrapping movements.

4. A machine according to claim 2, having a stationary tube located between the circle of needles and the fingers, which tube has a window at the wrapping zone to accommodate the fingers in their wrapping movements, and a separator for separating the old loops from the wrap loops on

the needles, which separator is attached to the tube and extends within the needle circle circumferentially across the window from one edge thereof to a point adjacent to the other edge.
